TIE SUPPORTER

Jacob R. Haas, Chicago, Ill.

Application September 12, 1935, Serial No. 40,210

13 Claims. (Cl. 2—155)

This invention relates to tie supporters.

It is an object of this invention to provide an improved tie supporter which is relatively simple and inexpensive in construction and efficient in use.

Another object of the present invention is to provide an improved tie supporter for supporting a necktie of the four-in-hand type upon the person of the wearer.

Other objects will appear hereinafter.

The invention consists in the novel combination and arrangement of parts to be hereinafter described and claimed.

The invention will be best understood by reference to the accompanying drawing showing the preferred forms of construction, and in which:

Fig. 1 is a perspective view showing a preferred form of the new tie supporter in applied position upon a collar;

Fig. 2 is a perspective view of a preferred form of the new tie supporter;

Fig. 3 is a fragmentary side elevational view of the preferred form of the new tie supporter shown in Figs. 1 and 2;

Fig. 4 is a fragmentary top plan view of the preferred form of the tie supporter shown in Figs. 1, 2, and 3; and

Fig. 5 is a perspective view of a modified form of the invention.

A preferred form of the present invention as shown in Figs. 1 to 4 inclusive of the drawing, is therein generally indicated at 10, and comprises a band or strip 11 of flexible, resilient material, preferably metal, which is adapted to encircle the neck of the wearer between the folds of a soft collar 12, as shown in Fig. 1.

The neck-encircling band 11 has a laterally projecting end portion or tongue 13 and the band 11 also has an end portion 14 which is bent back upon itself as shown in Fig. 2, this end portion 14 being provided with a slot 15, and the band 11 having openings 26 and 27 formed therein (Fig. 4) in alignment with the slot 15. The projecting portion or tongue 13 is adapted to be projected selectively through the apertures 26 and 27 into the slot 15 so as to hold the band 11 in position of use, as shown in Figs. 1 and 2.

Formed upon the neck-encircling band 11, adjacent one end of the same, is an upwardly extending attaching element or arm 16 and likewise formed upon the band 11, adjacent the arm 16, is an upward extension 17; while also formed in the band 11, adjacent the end portion 14, is an attaching element or arm 18, and formed

in the band 11, adjacent the arm 18 is an upward extension 19.

The present invention contemplates the provision of a four-in-hand tie, generally indicated at 20, and comprising a knot portion 21, and a body 24, and provided in the knot portion 21, one at each side of the same, are attaching elements in the form of eyelets or openings 22 and 23.

In the use of the new tie supporter, the tie 20 is attached to the supporter 10 by inserting 10 the attaching elements 16 and 18 into the attaching elements or eyelets 22 and 23, respectively, of the tie knot 21, whereupon the tie supporter 10, with the tie 20 thus attached thereto, may be arranged in position of use by extending the same around the neck of the wearer, between the folds of the collar, as shown in Fig. 1, with the attaching elements 16 and 18 and the attaching elements or eyelets 22 and 23 of the knot 21 disposed under the wings 25 of the collar 20 and hence rendered invisible when the tie supporter 10 and tie 20 are in use.

The projecting tongue 13 is then inserted through one of the openings 26 or 27 in the band 11 (Fig. 4), and through the slot 15 which is formed in the end portion 14 of the band 11. When the parts are thus positioned the extensions 17 and 19 project upwardly into the fold line of the collar and the knot 21 of the tie 20 rests upon the forwardly projecting tongue 13 (as shown in Figs. 1 and 3), and in this manner the supporter 10 and tie 20 are kept in proper wearing position and are caused to present a neat, attractive appearance.

A friction element, in the form of a rubber 35 sleeve or the like 41 (Fig. 2) is preferably provided on the band 11 so as to prevent the same from slipping under and relative to the folds of the collar when the tie supporter is in use, this friction sleeve engaging the folds of the 40 collar.

A modified form of the invention is shown in Fig. 5, is therein generally indicated at 28, and is formed from a single length or piece of wire 29.

The body or length of wire 29 is formed to 45 provide a cross bar 31 and formed in this cross bar 31 is a forwardly projecting tongue portion 32 which is adapted to extend under the knot of the tie when in use. Latchingly engaged with this tongue portion 32 of the cross bar 31 is a 50 hooked end portion 34 of the wire member 29. Likewise formed in the length of wire 29 is a hooked end portion 33 and a looped portion 30, this loop 30 being formed at one end of the cross bar 31 (Fig. 5).

Also formed in the cross bar portion 31 of the wire member 29 is a loop 35 which projects slightly above the body of the member 29, as shown in Fig. 5, for a reason to be explained 5 presently.

The modified form of the invention shown in Fig. 5 includes a tie 36 and formed in, or attached to, the knot portion 37 of the tie 36—37 are two attaching elements in the form of eyelets 10 or loops 38 and 39.

In the use of the combination tie and supporter shown in Fig. 5, the hooked end portion 34 of the cross bar 31 is inserted through the eyelet 38 and the latter is brought around to 15 the position in which it is shown in Fig. 5, and in which position the eyelet or attaching element 38 is disposed upon the loop or attaching element 39; the other eyelet or attaching element 20 39 being attached to the hooked end portion 33 of the member 29.

The supporter 28—29, with the tie 36—37 thus attached thereto, may then be inserted under the collar, between the folds of the same, in the same manner as that illustrated in Fig. 1 in connection 25 with the preferred form of the invention, the hooked end portion 34 of the supporter 28—29 being then latchingly attached to the tongue portion 32 of the cross bar 31.

When the parts are thus positioned, as in Fig. 30 5, the knot 37 of the tie rests upon the projecting tongue portion 32 of the cross bar 31 and the upper sides of the looped portions 30 and 35 bear up against the fold line of the collar, thereby keeping the tie supporter 28 in proper wearing 35 position upon the collar and at the same time keeping the tie 36 and its knot 37 in proper wearing position, and thus causing the same to present a neat attractive appearance when in use.

While I have illustrated and described the 40 preferred forms of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I 45 claim as new and desire to protect by Letters 50 Patent is:

1. A tie supporter comprising a flexible resilient member adapted to encircle the neck of the wearer between the folds of a collar, said member having an end portion provided with a slot, and 55 including a forwardly projecting end portion adapted to be projected through said slot so as to hold the supporter in encircling position about the neck of the wearer and between the fold lines of a collar against the action of its own resiliency when in use, said member including means for attaching a tie thereto.

2. A tie supporter comprising a flexible resilient member adapted to encircle the neck of the wearer between the folds of a collar, said member having an end portion provided with a slot, and 65 including a forwardly projecting end portion adapted to be projected through said slot so as to hold the supporter in encircling position about the neck of the wearer and between the fold lines of a collar against the action of its own resiliency when in use, said member having formed thereon a pair of spaced laterally projecting attaching elements for attaching a tie thereto.

3. A tie supporter comprising a flexible resilient member adapted to encircle the neck of the 70

wearer between the folds of a collar, said member having an end portion provided with a slot, and including a forwardly projecting end portion adapted to be projected through said slot so as to hold the supporter in encircling position about 5 the neck of the wearer and between the fold lines of a collar against the action of its own resiliency when in use, said member having formed thereon a pair of spaced laterally projecting attaching elements for attaching a tie thereto, and said member also having formed thereon, adjacent said attaching elements, a pair of upwardly extending portions adapted to be projected into the fold line of a collar when the said tie supporter 10 is in use.

4. A tie supporter comprising a flexible resilient member adapted to encircle the neck of the wearer between the folds of a collar, said member having an end portion provided with a slot, and including a forwardly projecting end portion 20 adapted to be projected through said slot so as to hold the supporter in encircling position about the neck of the wearer and between the fold lines of a collar against the action of its own resiliency when in use, said member including means for 25 attaching a tie thereto, and a sleeve arranged upon said flexible member and adapted to frictionally engage the folds of a collar and prevent the said tie supporter from slipping when in use.

5. A supporter for a four-in-hand necktie of 30 the type which includes a knot portion having a pair of spaced attaching elements in the form of loops, said supporter comprising a flexible resilient member adapted to encircle the neck of the wearer, between the folds of a collar, when in use, said member including means for detachably latching the relatively free end portions of the same in encircling position about the neck of the wearer, when in use, and against the action of 35 its own resiliency, and said member including means for detachably attaching said loops thereto.

6. A supporter for a four-in-hand necktie of the type which includes a knot portion having a pair of spaced attaching elements in the form of loops, said supporter comprising a flexible resilient member adapted to encircle the neck of the wearer, between the folds of a collar, when in use, said member including means for detachably latching the relatively free end portions of the same in encircling position about the neck of the wearer, when in use, and against the action of its own resiliency, said member including means for detachably attaching said loops thereto, said member including a forwardly extending 40 tongue portion adapted to underlie the knot of the tie when the supporter is in use.

7. A supporter for a four-in-hand necktie of the type which includes a knot portion having a pair of spaced attaching elements in the form of loops, said supporter comprising a flexible resilient member adapted to encircle the neck of the wearer, between the folds of a collar, when in use, said member including means for detachably latching the relatively free end portions of the same in encircling position about the neck of the wearer, when in use, and against the action of its own resiliency, and said member including means for detachably attaching said loops thereto, said member having means formed 55 thereon adapted to project under and into engagement with the fold line of the collar when the supporter is in use.

8. A supporter for a four-in-hand necktie of the type which includes a knot having a pair of 70

spaced attaching elements in the form of loops, said supporter comprising a length of flexible, resilient wire adapted to encircle the neck of the wearer between the folds of a collar when in use, 5 said length of wire having means formed therein for detachably latching the relatively free end portions of the same in encircling position about the neck of the wearer when the supporter is in use, and said length of wire having means formed 10 thereon for detachably attaching the said loops of the said knot portion of said tie thereto.

9. A supporter for a four-in-hand necktie of the type which includes a knot having a pair of spaced attaching elements in the form of loops, 15 said supporter comprising a length of flexible, resilient wire adapted to encircle the neck of the wearer between the folds of a collar when in use, said length of wire having means formed thereon for detachably latching the relatively free end 20 portions of the same in encircling position about the neck of the wearer when the supporter is in use, and said length of wire having means formed thereon for detachably attaching the said loops thereto, said length of wire having a forwardly 25 extending tongue portion adapted to project under the knot of the tie when the supporter is in use.

10. The combination of: a tie supporter, comprising a flexible resilient member adapted to encircle the neck of the wearer, between the folds 30 of a collar, when in use, said member including means for detachably latching the relatively free end portions of the same together in position to encircle the neck of the wearer, and a tie comprising a knot portion including a pair of spaced 35 attaching elements, said member including means for detachably attaching said attaching elements thereto.

11. The combination of: a tie supporter comprising a flexible resilient member adapted to encircle the neck of the wearer, between the folds of a collar, when in use, said member including means for detachably latching the relatively free 5 end portions of the same together in position to encircle the neck of the wearer when in use, and a tie comprising a knot portion including a pair of spaced 10 attaching elements in the form of loops, said member including a pair of spaced laterally projecting attaching elements for the reception of said loops.

12. The combination of: a supporter for a four-in-hand tie comprising a length of flexible resilient wire having means formed thereon for detachably latching the relatively free end portions of the same together in encircling position about the neck of the wearer and between the folds of a collar, when in use, and a four-in-hand tie comprising a knot portion including a pair of spaced 15 attaching elements, said length of wire having means formed thereon for detachably attaching said attaching elements thereto.

13. The combination of: a supporter for a four-in-hand tie comprising a length of flexible resilient wire having means formed thereon for detachably latching the relatively free end 20 portions of the same together in encircling position about the neck of the wearer, and between the folds of a collar, when in use, and a four-in-hand 25 tie comprising a knot portion including a pair of spaced attaching elements in the form of loops, said length of wire having means formed thereon for detachably attaching said loops thereto, and said length of wire having a forwardly 30 projecting tongue portion adapted to underlie the knot of the tie when in use. 35

JACOB R. HAAS.
